UNITED STATES PATENT OFFICE.

EDWARD A. LEFÈBRE, JR., OF BROOKLYN, NEW YORK.

PLURAL LAMP-SOCKET.

No. 896,122.

Specification of Letters Patent.

Patented Aug. 18, 1908.

Application filed August 28, 1907. Serial No. 390,442.

To all whom it may concern:

Be it known that I, EDWARD A. LEFÈBRE, Jr., a citizen of the United States, and a resident of Brooklyn, in the county of Kings and 5 State of New York, have invented certain new and useful Improvements in Plural Lamp-Sockets, of which the following is a specification.

My invention relates to plural lamp sockets 10 for incandescent electric lamps, the object being to simplify and cheapen the cost of construction of such sockets.

My invention consists in the details of construction and combinations of parts herein- 15 after more particularly set forth and then specified in the claims.

In the accompanying drawings; Figure 1 illustrates a vertical central section through a plural lamp socket constructed according 20 to my invention. Fig. 2 is a plan view showing the manner of mounting the individual lamp-holding sockets which form one terminal or contact for the lamp. Fig. 3 is a side elevation of the central contact shell, 25 detached from the rest of the device. Fig. 4 is a plan of the socket looking from below, the protecting casing and one of the individual lamp sockets being removed. Fig. 5 is a side elevation of the insulating block de- 30 tached from the rest of the device. Fig. 6 is an enlarged section showing the manner of mounting the individual lamp sockets more in detail.

In the preferred form of carrying out my 35 invention, 1 indicates the base formed preferably of a plate of metal and preferably provided with a threaded opening in the center for attachment to the usual wire carrying conduit. Secured to the face of the base 1 is a block of insulating material 2, such as 40 hard rubber, porcelain or other suitable substance. The insulating block 2 is provided with a central opening and consists of a projecting portion having squared sides and 45 from which a circular flange extends which bears against the base 1 when the parts are secured together. A cup - shaped shell 3 preferably formed of a solid piece of metal having oblique sides is secured to the block 2 50 within the central opening. A binding post 4 secured to the shell 3 provides terminal means for one of the wires leading into the socket.

5 indicates spring contacts preferably formed by cutting a tongue from the shell 3 and are engaged by the center contacts of the

lamps. By this construction a contact is obtained which has a solid backing yet is capable of yielding and always presses against the contact of the lamp. The tongue or contact 60 5 is preferably curved so that it will have a large area of engagement with the contact of the lamp.

Also mounted on the insulating block 2 and preferably against the squared sides of the projecting portion is a bowl - shaped frame consisting of side members or contact plates 6 upon which the individual lamp-holding sockets are secured, said plates being, 65 connected by a strip or strips of metal 6, 70 preferably integral with said plates or a connecting strip of insulation might be used if it is desirable to connect the lamps in series. The ends of the plates 6 which bear against the insulating block are provided with a 75 straight edge as shown more clearly in Fig. 2, which edge bears against the surface of the flange of the insulating block and prevents the plates from turning. The plates 6 are also provided with suitable openings to allow 80 the base of the lamp to pass through and make contact with the tongues 5. A suitable binding-post 7 secured to some suitable part of the frame forms a terminal for the 85 other wire of the circuit.

The wires of the circuit, namely those for attaching to the binding-posts or terminals 4 and 7 pass into the socket through the wire conduit attached to the base and through an opening 3' in the side of the shell 3 and then 90 secured to the said binding-posts.

The frame is preferably formed or stamped from one piece of metal, any desired number of plates 6 being provided to adapt the cluster to hold any number of lamps.

95 Mounted upon the contact frame and coinciding with the openings in the contact plates thereof, are the usual lamp holding sockets 8 which constitute the side contacts for the lamps as is usual in the art, the center contact making connection with the tongues 5 of the shell 3. The sockets 8 are secured to the plates 6 by clips or tongues 9 struck up from the metal in the plates and clamped down upon the usual lateral flange 8' of the 100 sockets 8. The ends of the said clips or tongues are preferably bent downward so as to engage suitable holes or slots formed in the flange 8', thus preventing the socket from 105 turning when the lamp is screwed in place. 110 By these means the lamp sockets are more cheaply and quickly secured to their supports.

than by soldering the flange 8' to the plates as has previously been the manner of securing them together in this art.

10 indicates an outer protecting shell or 5 casing, provided with suitable openings to allow the lamp sockets to pass through. An insulating collar 11 of porcelain or other suitable insulating substance is secured to the outer surface of the lamp sockets 8 and 10 passes through the openings in the casing 10 and prevents the shell or casing coming in contact with the various current carrying parts of the device.

When the lamps are screwed into their 15 sockets, they will be connected in parallel by the construction as shown, but, obviously, they could be connected in series if desired by breaking the connecting strip 6' and inserting a piece of insulation, in which case 20 each plate for the lamp sockets would have to be provided with a binding post.

While I have shown a socket adapted to supply current to two lamps, I do not limit myself to the same, as a cluster adapted to 25 supply current to any desired number of lamps might be constructed without departing from the spirit of my invention by striking up additional tongues 5 from the shell 3 and providing attendant lampholding sockets 30 constituting the side contacts.

What I claim as my invention is:

1. In a plural lamp socket, the combination 35 with a suitable base, of an insulating block provided with a square projecting portion and a central opening, secured to said base, a central contact shell secured to said block in said opening and socket-holding plates secured to the squared sides of said insulating block.

2. In a plural lamp socket, the combination 40 with a metallic base, of an insulating block provided with a squared projecting portion, and a central opening, secured to said base, socket holding plates secured to the squared sides of said insulating block, a 45 central contact shell secured to said block in said opening and spring contacts integral with said shell.

3. A plural lamp socket comprising a suitable base, an insulating block mounted thereon, lamp sockets supported by said block and a central contact shell secured at its edge to said insulating block and provided with spring yielding contacts integral therewith. 50

4. In a plural lamp socket the combination 55 with a suitable base, of plates secured to but insulated from said base, lamp holding sockets provided with a laterally projecting flange and tongues integral with said plates adapted to secure the flange of said sockets 60 to said plates.

5. In a plural lamp socket the combination 65 with a suitable base, of plates secured to but insulated from said base, lamp-holding sockets, laterally projecting flanges integral with said sockets provided with a plurality of slots and tongues integral with said plates adapted to press against the surface of said flanges, the ends of said tongues being hooked in said slots. 70

Signed at New York in the county of New York and State of New York this 26th day of August A. D. 1907.
